Patented Sept. 3, 1918

UNITED STATES PATENT OFFICE.

ISAAC NEWTON WEBER, OF NEW YORK, N. Y.

MECHANICAL TOY.

1,277,799.

Specification of Letters Patent. Patented Sept. 3, 1918.

Application filed July 13, 1918. Serial No. 244,798.

To all whom it may concern:

Be it known that I, ISAAC N. WEBER, a citizen of the United States, and a resident of the city of New York, borough of Manhattan, in the county and State of New York, have invented a new and Improved Mechanical Toy, of which the following is a full, clear, and exact description.

This invention relates to amusement devices, and has particular reference to certain details of construction and advantages hereinafter more fully set forth.

Among the objects of the invention is to provide a toy or amusement device calculated to afford unusual attractiveness because of its patriotic aspects, the apparatus including a movable figure that may represent in caricature a popular, but much hated, alien enemy, said figure being so poised in the apparatus as to be struck and knocked over by another feature of the apparatus or projectile in the nature of an allied soldier.

One of the objects of the toy or game is for children playing and enjoying the device to assume that the soldier is being caused to advance toward the enemy by suitable progressive stages, culminating in the ultimate defeat of the enemy and the capture of his stronghold.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views and in which—

Figure 1 is a front elevation of the game apparatus or toy in normal position.

Fig. 2 is a vertical sectional view of the same on the line 2—2, dotted lines indicating changed positions of the movable parts.

Fig. 3 is an enlarged detail view of the main upper portion of the device in the same position as in Fig. 1.

Fig. 4 is a plan view corresponding to Fig. 3.

Fig. 5 is a horizontal sectional detail on the line 2—2 of Fig. 1; and

Fig. 6 is a detail view of a part of the apparatus.

Referring now more specifically to the mechanism as an embodiment of a suitable construction, 10 represents a vertical standard or upright attached to a base 11, and being printed or otherwise provided on its face with suitable graduation marks or the like to indicate various stages in the assumed progress of the soldier toward the enemy. These graduation marks as indicated in Fig. 1 determine the boundaries of different fields or assumed territory. A guide rod 12 is arranged in front of the standard 10 and along this guide rod is arranged a scale 13 having numerical values arranged therealong to which reference may be made in the use of the toy or playing of the game.

14 indicates a projectile that preferably is intended to represent a soldier carrying a gun pointed toward the enemy. This projectile or figure is guided along the rod 12 and is held thereby from lateral displacement or loss, but is free to slide up and down the same. The normal position of this projectile is at the bottom of the guide rod as indicated in Figs. 1 and 2 and resting upon the end of a lever 15 journaled at 16 on the base. A plunger 17 rests upon the shorter arm 15' of the lever, and when the plunger is struck by a mallet 17' or the like the projectile or figure 14 will be given a sharp upward impulse along the guide rod 12, the distance in which the figure will move being dependent upon the accuracy of the blow of the mallet upon the plunger and the accompanying force thereof.

The enemy is characterized by a figure 18 supported upon a block 19 mounted on a horizontal axis 20 at the upper end of the standard. In the normal position the figure is supported in a substantially vertical plane just in front of the plane of the standard 10, and hence in front of the axis of the pivots 20. The figure 18, however, or some part associated therewith is positioned normally in the path of the upwardly movable projectile 14 and when the projectile is driven upward with sufficient force, impinging against the figure 18 or some other part associated therewith, said figure will be caused to topple rearward and swing down around the axis 20 and so the child may

say that the enemy is "killed". Obviously the figure may be restored to normal position by any suitable means as by grasping it for a subsequent playing of the game.

5   Added interest and amusement in the apparatus are afforded by the provision of a sounding device such as a gong or bell 21 shown as being secured to or against the rear face of the figure 18. This bell may be variously located and adapted to be struck or caused to sound by any suitable means either directly or indirectly as a result of the movement of the projectile. As shown herein, however, the block 19 is recessed at 19' and 10 into or through which the lower edge of the bell projects so as to be struck directly by the upper end of the projectile. The force of the blow serves immediately to ring the bell and if sufficiently strong will result in 15 the "killing" of the figure. It will thus be seen that different children playing the game may experience different results, for example the bell may be caused to ring without unseating the enemy, whereas a stronger and 20 better directed blow may cause the enemy figure to be toppled over. In any event irrespective of the height to which the projectile is thrown it will always return to the 25 normal position shown in Fig. 2 ready for a subsequent blow on the plunger.

Still another important feature of interest resides in the representation of the national colors at 22, the same being supported upon a staff 23 pivoted at 24 back of the standard 30 and near one edge thereof. Connected to the staff 23 is an extension or arm 25 which lies across the path of a cam 26 attached to the block 19. When the figure 18 is unseated and the block swings rearward and 35 downward the extension or cam 26 wiping against the arm 25 will cause the flag 22 to swing outward and upward and be displayed, representing conclusively the complete capture and possession of the enemy's 40 stronghold. When the enemy figure, however, is returned to normal position the flag will swing downward automatically back of the standard. The cam member during the 45 actuation of the flag may operate in or through a slot 26' formed in the upper end of the standard.

I claim:

1. In a device of the class set forth, the combination with a vertical standard, a

guide member thereon, a projectile guide on 5 and movable along said guide member, and means to project the projectile, of a movable figure located normally at the end of the standard in the path of the projectile and adapted to be thrown over rearward and 60 downward as a result of impact from the projectile.

2. In a mechanical toy, the combination of an upright standard, a projectile coöperating therewith, means to guide the projectile 65 upward along the standard, means to project the projectile, a figure movably connected to the upper end of the standard and located normally in the path of the projectile so as to be struck and moved rearward and downward thereby, and a sounding device caused to be sounded coincidentally with the operation of the projectile.

3. In a mechanical toy, the combination of a standard, a movable figure connected 75 to the upper end of the standard, a bell fixed to the movable figure, a projectile movable along the standard, and means to project the projectile upward toward the figure, the bell being so arranged as to be struck directly by the projectile so that the force of the projectile may not only ring the bell but cause the movement of the figure.

4. In a mechanical toy, the combination of an upright standard, a movable figure 85 connected to the upper end thereof, a projectile movable along the standard, means to project the projectile to cause the movement of the figure, and an emblem normally connected to the rear of the standard but 90 so positioned as to be moved into direct view by actuation of the movable figure as it is swung from normal position as a result of the impact of the projectile.

5. In a mechanical toy, the combination 95 of an upright standard, an emblem having a staff pivoted to the rear face of the standard, said staff having an extension, a movable member pivoted to the upper end of the standard, means to strike the movable 100 member and move it from normal position, and means carried by the movable member and adapted to coöperate with said staff extension to cause the emblem to be brought into view as a result of the movement of the 105 movable member from normal position.

ISAAC NEWTON WEBER.
